UNITED STATES PATENT OFFICE.

HEINRICH JACOB, OF FRIEDENAU, GERMANY, ASSIGNOR TO THE FIRM OF OPTISCHE ANSTALT C. P. GOERZ AKTIENGESELLSCHAFT, OF FRIEDENAU, NEAR BERLIN, GERMANY.

PROJECTILE DEVICE.

Application filed August 30, 1921. Serial No. 496,956.

To all whom it may concern:

Be it known that I, HEINRICH JACOB, a citizen of the German Republic, and resident of Friedenau, near Berlin, Germany, have invented certain new and useful Improvements in and Relating to Projectile Devices (for which I have filed applications in Germany, September 18, 1917; Austria, July 19, 1919; Sweden, July 24, 1919; Denmark, July 28, 1919; Hungary, July 30, 1919; and Czechoslovakia, February 6, 1920), of which the following is a specification.

The safe handling of projectiles which are to be thrown from aircrafts is difficult if the projectiles are to be thrown from small distance over the earth, so that they acquire during the downfall only a small velocity, and that consequently the usual safety devices, for instance those operated by centrifugal force and by rotating propellers or the like, can hardly be efficiently used.

This invention has for its purpose to overcome this difficulty and secures the effect aimed at thereby that the elements of the fuse of the projectile are made up in two different groups separated from each other, each of said groups being for itself of a kind that it can be handled comparatively dangerless, or that they contain only small quantities of explosives, so that an eventual explosion cannot do much harm.

The use of a projectile of this kind requires a device for bringing the two groups of elements of the fuse together in order to produce proper detonating of the explosive of the projectile.

A projectile in accordance with this invention and a device for bringing the two groups of elements of its fuse together at the moment of throwing off the projectile from an aircraft or the like is illustrated on the annexed drawing.

The projectile as a whole is designated with the numeral 1. The projectile is provided at its front end 2 with a cavity, wherein in a fulminant 3 with primer 4 is inserted. In the embodiment of the projectile shown on the drawing a safety body 5 of a slow burning composition is provided in front of said primer and fulminant in order to avoid unintentional ignition by contact. The safety body can be used as a retarder of the explosion of the projectile. The numeral 6 designates a cylindrical cavity at the front end of the projectile which is adapted to

receive the group of elements of the fuse which is separated from that group provided within the projectile itself. The elements of the fuse separated off from the projectile comprise an igniting pin 7 and an igniting cap 8 which are provided in a sleeve 9 which is formed with so thin wall that it is shortened on impact of the front end of the igniting needle 7, so that the needle 7 comes in contact with the igniting cap 8. The needle 7 is shown as being provided near its front end with a bore 10 receiving a lever 11 for inserting the sleeve with the needle and igniting cap into the cavity 6 of the projectile. 12 designates a sliding gate in front of the cavity 6 of the projectile which prevents the entrance of the sleeve with the needle and the igniting cap into said cavity as long as the projectile is firmly suspended on its carrier. The sliding gate 12 is connected to a cranked lever 13. The projectile is suspended on hooks 14 fixed on a reciprocating rod 15 provided with a cam 16 for the actuation of the cranked lever 13. The reciprocating rod 15 has also a slot 17 guiding a pin 18 of lever 11.

The operation and function of the whole projectile device as previously described and illustrated on the drawing is as follows:

On communicating to rod 15 a release movement levers 13 and 11 are actuated, the former so as to give free the entrance of the cavity 6 and the latter so as to push forward the sleeve 9 with the pin and the igniting cap and to insert it into the cavity 6 a short moment before the projectile is released by hooks 14. If for some reason the projectile should be retained on its carrier, the fuse can be again set to safety by communicating to rod 15 a movement in a direction opposite to that of the release movement. Such movement of rod 15 not only withdraws the sleeve from the cavity 6 but also closes the gate 12.

What I claim is:

1. A projectile device designed for being thrown off from elevated positions, particularly from aircrafts, comprising a projectile proper provided at its front end with a cavity containing at its bottom a provision of an explosive allowing safe handling of the projectile, a fuse member adapted to cause ignition of the explosive of the projectile when inserted in the front cavity of same,

holding or suspension devices for said projectile and said fuse member and means cooperating with the holding device for the projectile adapted to insert the fuse member into the front cavity of the projectile on release movement of the holding device for the projectile immediately before the projectile is released from its holder.

2. A projectile device designed for being thrown off from elevated positions, particularly from aircrafts, comprising a projectile proper provided at its front end with a cavity containing at its bottom a provision of an explosive allowing safe handling of the projectile, a fuse member adapted to cause ignition of the explosive of the projectile when inserted in the front cavity of same, holding or suspension devices for said projectile and said fuse member and means adapted to insert the fuse member into the front cavity of the projectile and further means for normally closing the cavity of the projectile for preventing unintentional entering of the fuse member into said cavity, both the actuating means for inserting the fuse member into the projectile cavity and the cavity closing door cooperating with the suspension device for the projectile and actuated thereby in dependence from each other in such manner that the cavity closing door is opened for the entrance of the fuse member only immediately before the release of the projectile takes place.

3. A projectile device designed for being thrown off from elevated positions, particularly from aircrafts, comprising a projectile proper provided at its front end with a cavity containing at its bottom a provision of an explosive allowing safe handling of the projectile, a fuse member adapted when inserted in front cavity of the projectile

proper to cause on impact of the projectile ignition of its explosive charge, holding or suspension devices for said projectile and said fuse member and means cooperating with the holding device for the projectile adapted to insert the fuse member into the front cavity of the projectile and to withdraw it therefrom on actuation of the suspension device in opposite directions.

4. A projectile holding or suspension device comprising a reciprocating holding member for a projectile proper, a holder or guide for a fuse member, and a fuse actuating member in operative connection with said reciprocating projectile holder adapted to displace a fuse within said guide substantially parallel to the direction of movement of the reciprocating member.

5. A projectile holding or suspension device comprising a reciprocating holding member for a projectile proper, a guideway and holder for a fuse member for the projectile arranged substantially parallel to the direction of movement of the reciprocating member, a fuse actuating member adapted to displace a fuse within said guideway, a slide gate arranged transversely to said guideway, the fuse actuating member and the slide gate both in operative connection with the reciprocating projectile holding member and so coordinated to each other that the slide gate is withdrawn from the area of the guideway when the fuse actuating member advances towards the gate.

In testimony whereof I have signed this specification in the presence of two subscribing witnesses:

HEINRICH JACOB.
